UNITED STATES PATENT OFFICE.

JOHN W. HOUSEBERG, OF PITTSBURGH, PENNSYLVANIA.

LATHE TOOL-HOLDER.

1,017,974.

Specification of Letters Patent. Patented Feb. 20, 1912.

Application filed March 15, 1911. Serial No. 614,537.

To all whom it may concern:

Be it known that I, JOHN W. HOUSEBERG, of Pittsburgh, in the county of Allegheny and State of Pennsylvania, have invented 5 certain new and useful Improvements in Lathe Tool-Holders, of which the following is a specification.

My invention relates to improvements in tool holders for lathes of various types, and 10 more particularly to new and improved binding or tightening means for holding the cutting tool in the desired operative position.

In tool holders of the class to which my invention relates, as heretofore constructed, a threaded member has been employed for making direct contact with the tool and co-operating with another threaded member for binding or clamping the tool in the desired 15 position. In such constructions considerable trouble has been encountered by reason of the threaded member, having direct contact with the tool, binding or becoming wedged in the internally coöperating threaded member due to the great strain to which the externally and internally threaded members are subjected. In practice, it frequently 20 happens that the threaded tool contacting or engaging member becomes wedged in the threaded member in which it is inserted, thus necessitating considerable labor to remove the threaded wedged member.

An object of my invention is to provide a simple and efficient tool holder and binding 25 or clamping means that will obviate the disadvantages above mentioned of tool holders employing a threaded tool engaging member.

A further object of the present invention 30 is to provide a tool holder comprising an unthreaded tool engaging member or plunger and coöperating means for forcing the tool engaging member into contact with the tool and maintaining it in engagement there- 35 with.

In the accompanying drawing, which 40 illustrates applications of my invention; Figure 1 is a side elevational view of a holder embodying my invention, shown in connection with a portion of a lathe; Fig. 2, 45 a part elevational view and a part sectional view, the section being taken on the line II-II of Fig. 1; Fig. 3, a top plan of the form of Fig. 1; and Fig. 4, a part elevational view and a part sectional view of a 50

modified form of my invention shown in connection with a portion of a turret-lathe.

Referring to the drawing and first to the form of Fig. 1, 1 designates the body-portion of my improved tool holder, said body-portion being shown in the form of a tool-post. The body-portion comprises a hollow cylindrical member having a central unthreaded bore 2, an externally threaded upper portion 3, and an annular flange 4 disposed on the lower end thereof. Said flange 4 is adapted to be entered in a groove 5 of a lathe portion 6. The body 1 is further provided with a laterally extending tool receiving slot 7 for a tool as 8.

Designed to coöperate with the externally threaded upper portion of the body, I provide an internally threaded cap 9 having its threads 10 adapted to engage the threads 11 of the said upper portion of the body. Cap 9 is preferably of the form shown and has formed integral therewith a nut 12.

Having a portion located within the hollow cap 9 and extending downwardly therefrom into the bore 2 of the body 1 is a separable member or plunger 13. Plunger 13 as illustrated and as preferred comprises a central cylindrical portion having on the upper end thereof an annular head 14, and on the lower end thereof a contracted projecting member 15, the latter being designed to make contact with the cutting tool 8.

16 designates the usual ring or gib employed in tool holders of this class and is designed to support the tool 8 as clearly 90 shown by the drawing when the tool is clamped in operative position by the member 13.

From the foregoing it will be noted that I dispense with a threaded tool binding or 95 clamping member and provide in place thereof a separable loose member free of threads and other parts liable to be injured in clamping the tool on the ring 16, also that said member 13 is well adapted to take 100 care of all the strains, etc., to which it is subjected in practice, and, further there is no liability of its becoming bound or wedged in its inclosure.

In the form of Fig. 4, I have shown a 105 modified form of my invention particularly designed to be used in connection with a turret-lathe. In this latter embodiment of my invention, 17 designates a portion of a turret to which the tool holder is secured 110

and in this form of my invention the body-
portion or hollow standard 1^a is formed
with a bearing member or nut 18 and a lower
threaded portion 19, the latter being adapted
to be entered in an internally threaded opening
20 of the turret. In addition to the
elements just mentioned, the body is formed
with a central unthreaded bore 2^a and with
an externally threaded upper portion 3^a cor-
10 responding with 2 and 3 of the form of
Fig. 1. The remaining parts namely the
member 13^a and the cap 9^a and the operation
thereof are substantially the same as in the
form of Fig. 1. The cap 9^a in this latter
15 form is shown provided with an oil passage
21 designed for the purpose of introducing
oil to the head of the member 13^a if desirable.

What I claim is:

- 20 1. In a tool holder, the combination of an externally threaded member or body having a smooth bore, an internally threaded member coöperating with the externally threaded member or body, and a separable un-
25 threaded tool-clamping member adapted to make direct contact with the tool, said separable member arranged in the bore of the body and projecting into the externally threaded member.
- 30 2. In a tool holder, the combination of an externally threaded member or body having a smooth bore, an internally threaded cap coöperating with the externally threaded member or body, and a separable loose tool-
35 clamping member adapted to make direct contact with the tool, said separable member arranged in the bore of the body and projecting into the cap.
3. In a tool holder, the combination of a
40 body or standard having an upper externally threaded portion and an unthreaded

bore, an internally threaded cap coöperating with the threaded body or standard, and tool binding means comprising a separable plunger adapted to make direct contact with 45 the tool, said plunger arranged in the bore of the body or standard and projecting into the cap.

4. In a lathe tool holder, the combination with a support, of an externally threaded member or body having a central unthreaded bore, an internally threaded cap coöperating with the externally threaded body, and a separable unthreaded tool-clamping member adapted to be moved into binding engagement 50 with the tool by the movement of the cap on the body.

5. In a lathe tool holder, the combination with a support, of a body or standard having engaging means at its lower end, an 60 upper externally threaded portion and a smooth bore, an internally threaded cap coöperating with the externally threaded portion of the body, and a separable tool-clamping plunger adapted to be brought 65 into binding engagement with a tool by the movement of the cap on the body.

6. In a tool holder, the combination of an externally threaded member or body having a smooth bore, an internally threaded cap coöperating with the externally threaded member or body, and a separable tool binding member provided with a head, said member having a portion located in the smooth bore 70 of the body and its head in the cap.

In testimony whereof I affix my signature
in presence of two witnesses.

JOHN W. HOUSEBERG.
